UNITED STATES PATENT OFFICE.

NORA T. BURKE, OF STONEHAM, MASSACHUSETTS.

FOUNTAIN PEN.

Application filed August 31, 1928. Serial No. 303,279.

This invention relates to fountain pens and has particular relation to the prevention of sweating of the pen when not in use.

I have observed that when fountain pens are capped and not in use, sweating occurs on the inside of the cap. After the sweating has taken place and the cap is loosened, the sweat falls and comes into contact with the finger piece of the pen, thus exposing the fingers of the writer to the probability of becoming soiled.

It is the primary object of my invention to provide a means for preventing the tendency for fountain pens to sweat.

Another object of my invention is the provision of a means for sealing the space around the pen point and feeding device of a fountain pen.

Another object of my invention is the provision of a flexible sealing means around the pen point and feeding device.

Another object of my invention is the provision of a soluble sealing means as a soluble rubber, placed about the pen point and feeding device of a fountain pen.

Referring to the drawing wherein I have illustrated a preferred embodiment of my invention.

Figure 1 is a side elevation of my pen illustrating how the same may look after application of my invention thereto.

Figure 2 is a cross section on the line 2—2 of Figure 1, but showing the cap in place.

Similar reference characters refer to the same or similar parts throughout the several views of the drawing.

In attempting to prevent the well known "sweating" of fountain pens, I found that by sealing up the end of the pen around the pen point and feeder piece, I could prevent the tendency to sweat by preventing the creeping of the ink along the outside of the feeder piece and pen point.

One way of sealing the end of the fountain pen and which I found to be satisfactory was to pour a solution of rubber into the space around the feeder piece and pen point and permit the same to become dry through the evaporation of the liquid vehicle.

In the drawing, 10 designates the main casing of the fountain pen, 11 the cap and 12 the ink reservoir.

The feeder piece 13 is provided with a recess which receives the pen point 14. In the feeder piece 13 is the usual ink duct 15.

The pen point 14 and the feeder piece 13

are placed together and are fitted tightly in the finger piece 16 which in turn is secured in the end of the main body of the casing 10 by the screw threads 16a.

Apparently due to the fact that ink gets on the surface 17 of the outside of the feeder piece 13, there is produced the sweating already referred to. By holding the pen in an upright position, the pen point 14 uppermost, it is possible to pour soluble rubber or any other suitable substance 18 in the top of the pen. This forms a moisture proof plug which seals the joints between the finger piece 16, the pen point 14 and the feeder piece 13.

The soluble rubber used in the embodiment illustrated, is resilient and clings to the sides of the adjacent parts, thus preventing the passage of the ink from the ink reservoir 12.

While I have shown and described in detail one embodiment of my invention, I desire to have it understood that I do not limit myself to the exact showing and that modifications and changes may be made without departing from the spirit of my invention and within the scope of the appended claims.

Having described my invention what I claim and desire to secure by Letters Patent is:—

1. A fountain pen having a casing, a finger piece at the end of the casing, a feeder piece and a pen point carried by and within the finger piece, the two latter being exposed from and beyond the end of the finger piece and a cast-in-place plug for sealing the joint between the pen point, feeder piece and finger piece.

2. A fountain pen having a casing, a finger piece at the end of the casing, a feeder piece and a pen point carried by and within the finger piece, the two latter being exposed from and beyond the end of the finger piece and a cast-in-place flexible plug for sealing the joint between the feeder piece and finger piece.

3. A fountain pen having a casing, a finger piece at the end of the casing, a feeder piece and a pen point carried by and within the finger piece, the two latter being exposed from and beyond the end of the finger piece and a cast-in-place flexible rubber plug for sealing the joint between the feeder piece and finger piece.

In testimony whereof I hereby affix my signature.

NORA T. BURKE.
